UNITED STATES PATENT OFFICE.

EDMUND SYHRE, OF DRESDEN, GERMANY.

FELT FOR PIANO HAMMERS.

Application filed April 1, 1920. Serial No. 370,593.

To all whom it may concern:

Be it known that I, EDMUND SYHRE, a citizen of Germany, residing at Dresden, in the Republic of Saxony, Germany, have invented certain new and useful Improvements in Felt for Piano Hammers, of which the following is a specification.

This invention relates to an improved method for felting piano hammers.

10 In the accompanying drawings:—

Figs. 1 to 4 illustrate the usual known method.

Figs. 5 and 6 being illustrations of my improved method.

15 With the known method for the felting of piano hammers approximately square felt plates of wedge-shaped longitudinal section (Fig. 1) are used, which through cuts which are not straight but run at a certain angle 20 the one towards the other is divided into strips *a* (Fig. 4). The cores *c* of the hammer heads which at least for the deeper notes are covered with the so-called under felt *b*, are pressed, according to most of the usual 25 manufacturing methods, upon the back of such a felt strip after they have been previously fastened together by means of a clamping instrument.

The strip of felt is thus pressed into a 30 channel which gets gradually narrower from the bass to the treble and the lateral flaps of the felt strip after they have been painted with glue are pressed by lateral cheeks against the lateral surfaces of the cores *c*. In this 35 manner rather strong pressure of the strip of felt is effected which gradually increases from the bass to the treble, the reduction in the size of the strip being shown in Figs. 2 and 3 and from the dotted lines in Fig. 1.

40 This unequal compressing of the felt corresponds to the requirement that the hammers in the bass part may be comparatively soft but that those in the treble part must be very hard for the reason that the short strings of 45 the highest tones sound only with sufficient fullness and strongness under a very hard blow. This exigence is taken into consideration already when the felt plates are being manufactured and in such a measure that 50 for the unequal compressing of the felt when felting the hammers there remains very little to be done in this respect.

In Fig. 1 of the drawings there is indicated by the hatching which indicates the fiber, 55 how with the gradual decrease of the height

of the felt plate its density and hardness gradually increase.

It has been proposed to obtain this gradual increase in the hardness of the felt by the distribution and treatment of the felt 60 strip but there is not always obtained the desired result to get felt plates of the required dimensions and the desired graduation of density and hardness which demands, in every case well skilled factory hands and 65 very expensive handwork.

There has further to be taken into consideration that, as far as the quality of the felt is concerned, that part of the felt plate destined for the treble must always determine 70 the quality so that the very best and most expensive felt has to be used for instruments of medium quality for which, without any inconvenience as regards the fullness and lasting of the tone, the felt could well be of 75 somewhat lower quality at least for the lower tones.

It is not possible with the well known manufacturing methods to make uniform 80 felt plates from felt of assorted qualities. It must not be overlooked that it is not easy to cut the felt plate into strips *a* owing to the wedge shape of the plate and of the strips and that this cannot always be done 85 without waste.

According to my invention a uniform felt strip reaching over the entire length of the set of hammer heads is no longer used. A strip of corresponding length is composed of 90 several pieces, in this manner essential technical effects as well as economic advantages are obtained. It is no longer necessary that the pieces which compose the felt plate be of wedge-shaped cross section but they may be flat with beveled edges as shown. Herefrom follows at first the advantage that it is 95 easy to cut out the pieces from a felt sheet without any waste.

In this manner I have solved the problem by making the felt for the covering of piano 100 hammers either in sheets or in strip roll form, each piece of felt being throughout of uniform quality. The manufacturer can thus produce perfect hammers for instruments of medium quality without considerable expense, as for the higher tones he can use felt of even better quality than it was possible hitherto, he being able to use for all the other hammers a felt of a much cheaper quality.

In Figs. 5 and 6 a felt strip made accord- 110

ing to the improved method is shown in longitudinal section and in plan view respectively. The strip is composed of pieces a^1, a^2, a^3, a^4 made from felt.

- 5 These pieces a^1, a^2, a^3 and a^4 are independent from one another and are of different grades of felt or other desired material, and are placed end to end in their proper sequence of size and quality for covering the 10 hammer heads in the ordinary manner. It is thus possible to utilize felt of a high grade for use with the short thin wires under high tension and to use cheaper grades of felt where softer hammer heads 15 are desirable and where there is less wear and disintegrating strains on the feet. Figs. 5 and 6 show these separate pieces or sections of the strip arranged in proper order according to size.
- 20 The steps which can be seen in Fig. 5 and which are caused by the difference in thickness of the parts, will automatically disappear when the cores of the hammer heads are 25 pressed upon the felt strip. If the dotted line indicates as in Fig. 1, the final compression of the felt the graduation of the thickness and hardness which, according to the known method of manufacture is obtained 30 through the wedge shape of the felt plate and through the different distribution of the fibers along the entire length of the plate, is now obtained quite automatically through the compression of the pieces of originally 35 prismatic shape. At the joints of the pieces always one hammer will be wasted in the covering of which the edges of the two adjacent pieces of felt join but this does not matter, there being generally added several

odd hammers to every set of hammer head cores. To avoid the waste of hammers 40 at the joining lines there could be inserted between each group of hammers filling pieces c^1 which are somewhat slightly larger than the cores (Fig. 5). Otherwise the felting method does not differ from the usual manufacturing method.

I claim:—

1. A covering for hammer heads comprising a plurality of sections of different dimensions and of different grades of material, the 50 sections being of lengths corresponding to the separate groups of hammer heads from the base to the treble and being arranged end to end and with the sections of the better 55 grades of material cut in smaller sizes than the sections of poorer grades of material for use in the treble end groups and the sections graduated according to size and grade from the base end to the treble end of the covering.

2. A covering for felting piano hammers, composed of a row of group length sections of covering material arranged end to end, and the sections being of different thicknesses and widths and diminishing in thickness and increasing in the grade of the material of the sections throughout the groups from the base to the treble of the hammer heads.

In testimony whereof I affix my signature 70 in presence of two witnesses.

EDMUND SYHRE.
